UNITED STATES PATENT OFFICE.

JAMES H. NOLAN, OF ROCKFORD, ILLINOIS.

DESIGN FOR A HAMMER.

43,639.

Specification for Design.

Patented Feb. 25, 1913.

Application filed November 15, 1912. Serial No. 731,605. Term of patent 7 years.

To all whom it may concern:

Be it known that I, JAMES H. NOLAN, a citizen of the United States, residing at Rockford, in the county of Winnebago and State of Illinois, have invented a new, original, and ornamental Design for Hammers, of which the following is a specification, reference being had to the accompanying drawing, forming part thereof.

On the drawing, Figure 1 is a side view,

Fig. 2 a front view, Fig. 3 a plan view and Fig. 4 a bottom view of a hammer, showing my new design.

I claim:

The ornamental design for a hammer, as shown.

JAMES H. NOLAN.

Witnesses:

A. O. BEHEL,
JOHN F. McCANNA, Jr.
